UNITED STATES PATENT OFFICE.

AUGUST P. HEDBERG, OF MILFORD, MASSACHUSETTS.

FLYING MACHINE.

1,417,602.

Specification of Letters Patent.

Patented May 30, 1922.

Application filed June 9, 1919. Serial No. 302,871.

To all whom it may concern:

Be it known that I, AUGUST P. HEDBERG, a citizen of the United States, residing at Milford, in the county of Worcester and State of Massachusetts, have invented certain new and useful Improvements in Flying Machines, of which the following is a specification.

The invention relates to aeroplanes and more particularly to flying machines of the paddle wheel type which are provided with self-sustaining and lifting mechanism and has for its object to devise lifting mechanism which may also be utilized as propelling and sustaining means, whereby it is possible to poise the machine over a given point, whereby observations may be made or projectiles dropped upon any selected or required spot.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

Referring to the drawings hereto attached, Fig. 1 represents an aeroplane embodying the invention in side view; and

Fig. 2 is a front view thereof, parts being broken away.

Corresponding and like parts are referred to in the following description and indicated in both views of the drawings by like reference characters.

The body of the machine is designated by the numeral 1 and may be of any construction or outline and as shown is made tapering at opposite ends and is mounted upon wheels 2, whereby landing may be made with safety or the machine trundled from one place to another. For proper steering, the machine is provided with a vertical rudder 3 and a horizontal rudder 4, said rudders being adapted to be adjusted in any well known manner. Side planes 5 give stability to the machine and assist materially in sustaining the same when in flight.

The lifting and propelling mechanism is disposed above the body of the machine and partakes of the nature of an aero-drum which is horizontally disposed and comprises plates 6 and wings 7, the latter being pivoted intermediate of their ends to the plates 6 by means of shafts 8. The wings 7 are curved and are disposed to have end portions over-

lap. There may be any number of wings 7 and the same may be of any length and width. Standards 9 are secured to opposite sides of the body 1 and support the aero-drum and cooperating parts. A shaft 10 is supported in the standards 9 and carries the aero-drum and coacting parts. Each of the shafts 8 has an arm 11 projecting therefrom and forked at its outer end. The forked end of the arm 11 carries wheels 12 and 13 which are mounted upon an axle supported by the forked members of the arm. The wheel 12 is of larger diameter than the small wheels 13 at the sides thereof. A track 14 is provided for the wheel 12 to travel upon and other tracks 15 are disposed at the sides of the track 14 for the wheels 13 to coact with. The wheels 13 bear against the inner faces of the tracks 15, whereas the wheel 12 travels upon the outer face of the track 14. In this manner the inner forked end of the arm 11 is positively moved inward and outward, thereby controlling the position of the wing connected therewith and holding said wing positively in the predetermined position in its travel.

A sector arm 16 is connected with the tracks 14 and 15 preferably by means of the shaft 10 so that adjustment of the arm 16 will effect a corresponding adjustment of the tracks 14 and 15. It is to be understood that the parts are duplicated at each side of the machine. Each sector arm 16 has its edge portion toothed, as indicated at 17 and in mesh with a worm 18 on a longitudinal shaft 19, the two shafts 19 being geared to a transverse shaft 20, so that both longitudinal shafts 19 and sector arm 16 may be simultaneously operated when it is required to adjust the tracks 14 and 15. The tracks 14 and 15 are of cam shape and have a parallel arrangement so as to maintain positive contact with the wheels 12 and 13 at every point in the revolution of the aero-drum. The tracks 14 and 15 serve to project the wings at a determinate point in the revolution of the aero-drum and to fold said wings in another position in the revolution of the drum.

The aero-drum is positively rotated and this is accomplished by worm gearing, the same consisting of a worm gear 21 rotatable with each of the plates 6 and a worm 22 rotatable with a vertical shaft 23 journaled to the standards 9. Bevel gearing 24 connects the lower end of each vertical shaft 23 with the shaft of an engine 25 mounted

upon the deck of the body 1. The worm gear 21 and aero-drum are mounted loosely on the shaft 10, so as to rotate freely thereon without interfering with the adjustment of the arm 16 and cam tracks 14 and 15 which as stated are connected to the shaft 10 which latter in turn has the arms 16 fastened thereto, whereby the arm 16, shaft 10 and cam tracks 14 and 15 move together.

10 Planes 26 project laterally from the machine and are adapted to tilt about an axis coinciding with the shaft 10. A suitable frame 27 is connected to the inner end of each of the planes 26 and depends therefrom and is adapted to be adjusted forwardly and rearwardly at its lower end to change the angle of the planes 26 as may be required. The frame 27 comprises a plurality of bars which are disposed to form a substantial and light structure. A cord or rope 28 is attached to the lower end of each of the frames 27 and extends forwardly and rearwardly therefrom and passes around guide pulleys 29 and is wrapped about a transverse shaft 30. Rotation of the shaft 30 effects a movement of the cord or rope 28 so as to move the frame 27 and adjust the inclination of the planes 26. Both planes are simultaneously adjusted because the connections employed in conjunction with one are duplicated with the other and both cords or ropes 28 are simultaneously operated by the shaft 30.

When the machine is at rest and it is required to rise, the cam tracks 14 and 15 are adjusted to cause the wings 7 to extend horizontally, so that upon moving downward the air beneath is compressed and as a consequence the machine is lifted. When the machine is rising, the wings 7 begin to project horizontally from the upper portion of the aero-drum and to fold after reaching the lower portion of the aero-drum and while travelling from the lower to the upper position. After the machine has risen to the required elevation, it is propelled by means of the aero-drum by adjusting the cam tracks 14 and 15 so as to project the wings vertically upon the forward side of the drum and during their travel from front to rear, said wings folding upon the rear and top side of the drum during such

time. It is also obvious that the cam tracks 14 and 15 may be adjusted so that advantage may be taken of the wings to control the descent of the machine when it is required to make a landing. By proper adjustment of the cam tracks 14 and 15, the wings may be projected from the drum and fold thereagainst at any point in the revolution of the drum, whereby to control the ascent, the flight and the descent of the machine, as will be readily understood.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In an aeroplane, a body, a superstructure, and a horizontal shaft supported by said body, rotary plates and overlapping curved wings pivoted intermediate their ends adjacent the periphery of said plates, rollers carried by the inner ends of each of said wings, cam tracks for said rollers and means for adjusting said tracks for varying the effective air engaging surfaces of the wings during their revolution.

2. In an aeroplane, a body, a superstructure and a horizontal shaft supported by said body, rotary plates and overlapping curved wings pivoted intermediate their ends adjacent the periphery of said plates, rollers carried by the inner ends of each of said wings, cam tracks for said rollers, sector arms connected to said tracks and gearing for adjusting said sector arms and tracks to vary the effective air engaging surfaces of the wings during their revolution.

In testimony whereof I affix my signature in presence of two witnesses.

AUGUST P. HEDBERG.
